W. H. HOLDER,
ELECTRICAL CONTROLLER,
APPLICATION FILED JUNE 14, 1918.

1,352,896.

Patented Sept. 14, 1920.

Inventor
William H. Holder
By Frank B. Hubbard, Attorney

UNITED STATES PATENT OFFICE.

WILLIAM H. HOLDER, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRICAL CONTROLLER.

1,352,896.

Specification of Letters Patent. Patented Sept. 14, 1920.

Application filed June 14, 1918. Serial No. 240,092.

To all whom it may concern:

Be it known that I, WILLIAM H. HOLDER, a citizen of the United States, residing at Milwaukee, in the county of Milwaukee and State of Wisconsin, have invented new and useful Improvements in Electrical Controllers, of which the following is a full, clear, concise, and exact description, reference being had to the accompanying drawing, 10 forming a part of this specification.

This invention relates to electrical controllers of the rotatable drum type.

Among the objects of the invention is to provide a controller of the character stated 15 wherein the various operative parts are so arranged as to occupy a minimum of space and to be fully and readily accessible.

A further object is to provide in controllers of the character stated, means facilitating 20 the arrangement and assembly of certain of the fixed contacts in opposed relation to other of said contacts while maintaining the necessary insulation therebetween.

Other objects and advantages will herein- 25 after appear.

In the accompanying drawing, wherein is illustrated an embodiment of the invention,

Figure 1 is an end view of the controller; while,

Fig. 2 is a fragmentary side elevational view further illustrating certain details.

Referring to the drawing, the same illustrates a controller drum 1 rotatably mounted within suitable brackets 2, the latter being secured to an insulating support or base 3 by means of bolts 4. A plurality of contact segments 5 are peripherally secured to the drum 1 and adapted to coöperate with relatively fixed contact fingers 6 pivotally 40 and resiliently carried by a finger board 7 which is fixedly mounted upon suitable extended portions 8 of the brackets 2.

The contact fingers 6 are arranged in two groups, the respective groups being located 45 upon opposite sides of the finger board 7 to extend upon opposite sides of the drum 1, corresponding pairs of fingers being arranged in the same plane transversely of the drum and finger board, the latter having substantially plane side surfaces 9, 10 for 50 connection of the contact fingers thereto.

Each of the contact fingers 6 is pivotally mounted upon a finger support 11 having a

stop for limiting movement of the finger in one direction, while a spring 12 serves to bias 55 said finger against said stop in a well known manner. Said finger supports 11 are rigidly mounted upon the finger board 7 by means of bolts 13, each of said bolts having its head countersunk below the opposite surface of said finger board, as illustrated. Furthermore, each of said bolts is also utilized for attachment of a terminal 14 60 for the respective contact fingers. For insuring accurate positioning of the finger supports each of the same is provided with an additional positioning stud 15 screwed therewithin from the opposite side of the finger board and having its head counter- 65 sunk as shown.

In order to permit mounting of the contact fingers upon both sides of the finger board and in the same transverse plane as described, the opposite sets of finger supports are relatively staggered laterally of 70 the finger board, as illustrated, whereby the bolt heads of one finger support are not covered by the opposite finger support. Furthermore, in order to permit the use of contact fingers of equal length on both sides 75 of the finger board and also to insure that the effective radii of said fingers shall bear a tangential relation to the controller drum at their respective points of contact therewith, the finger board is so arranged with 80 respect to said drum that the surfaces 9 and 10 are disposed angularly to the plane of symmetry of the groups of contact fingers with respect to the center of the drum. The projecting portions 8 of the brackets 2 90 are therefore provided with attaching surfaces at a suitable angle to said plane of symmetry, the finger board being secured directly to said surfaces of the bracket portions.

Since the contact fingers upon opposite sides of the finger board extend at different angles from the attaching surfaces of the latter, the finger supports on opposite sides of said finger board are bent at different 95 angles but are otherwise, in all respects, similar.

By the above arrangement the pivot points of the contact fingers are all located symmetrically with respect to the center of 100 the drum irrespective of the staggered

mounting of the contact supports, while assembly of the controller is greatly facilitated.

5 The hereinbefore described mechanism is housed within a casing 16 shown in broken lines and which is preferably formed integral with the base 3 or rigidly secured thereto, said casing being provided with a removable top cover 17.

10 It is thus obvious that owing to the particular arrangement described the active parts of the controller are rendered accessible for inspection or repair upon removal of the cover 17, while the length of the

15 controller necessary to provide for a given number of contacts is materially reduced without substantial increase in other dimensions.

What I claim as new and desire to secure 20 by Letters Patent is:

1. In combination, a rotatable drum, a fixed support and contact fingers of uniform length fixed to said support in an opposed relation, said support being disposed relatively to said drum to provide for mounting of said contact fingers upon the former in a common plane but in an offset relation to engage said drum at substantially diametrically opposed points.

2. In combination, a rotatable drum, a plurality of contact fingers of uniform length to engage therewith, and common supporting means for said fingers, said means providing for support of said fingers 35 in an opposed relation in the same plane transverse with respect to the axis of said drum to engage the latter at substantially diametrically opposed points and in a staggered relation with respect to said supporting means.

3. In combination, a rotatable drum, a plurality of contact fingers of uniform length arranged symmetrically with respect thereto, and common supporting means for 45 said contact fingers having opposed surfaces arranged angularly to the plane of symmetry of said fingers with respect to the center of said drum to provide for mounting of said fingers in an opposed relation upon said surfaces to engage said drum tangentially and at substantially diametrically opposed points, the fingers mounted upon the respective opposed surfaces of said supporting means being relatively staggered laterally of said supporting means.

4. In combination, a rotatable drum, a plurality of contact fingers of uniform length arranged symmetrically with respect thereto, and common supporting means for 60 said contact fingers having opposed surfaces

arranged angularly to the plane of symmetry of said fingers with respect to the center of said drum to provide for mounting of said fingers in an opposed relation upon said surfaces to engage said drum tangentially and at substantially diametrically opposed points, the fingers mounted upon the respective opposed surfaces of said supporting means being relatively staggered laterally of said supporting means, and a 70 housing for said parts having a removable cover located adjacent said supporting means for rendering all of said fingers readily accessible.

5. In combination, a rotatable drum, a plurality of contact fingers of uniform length arranged symmetrically with respect thereto and in opposed relation to one another in planes perpendicular to the axis of said drum for coöperation therewith and 80 supporting means for said contact fingers comprising a plurality of finger supports having said contact fingers pivotally mounted thereon respectively and a rigidly secured finger board having opposed mounting surfaces to which said finger supports are bolted in opposed relation, the finger supports thus opposed to one another being relatively staggered laterally of said finger board to provide for spacing of each finger 90 support from the securing bolt of the opposed finger support.

6. In combination, a rotatable drum, a plurality of contact fingers of uniform length arranged symmetrically with respect 95 thereto and in opposed relation to one another in planes perpendicular to the axis of said drum for coöperation therewith and supporting means for said contact fingers comprising a plurality of finger supports 100 having said contact fingers pivotally mounted thereon respectively and a rigidly secured finger board having opposed mounting surfaces to which said finger supports are bolted in opposed relation, the finger supports thus opposed to one another being relatively staggered laterally of said finger board to provide for spacing of each finger support from the securing bolt of the opposed finger support, said mounting surfaces of said finger board being arranged angularly to the plane of symmetry of said contact fingers with respect to the center of said drum for causing said opposed contact fingers to coöperate with said drum tangentially and at substantially diametrically opposed points.

In witness whereof, I have hereunto subscribed my name.

WILLIAM H. HOLDER.
